A. A. HIRSH

TOOTH CLEANER

Filed Nov. 17, 1924

FIG. 1.

FIG. 2.

Inventor

A. A. HIRSH.

By

David D. May Jr. - Attorney

UNITED STATES PATENT OFFICE.

ALBERT A. HIRSH, OF NEW YORK, N. Y.

TOOTH CLEANER.

Application filed November 17, 1924. Serial No. 750,375.

To all whom it may concern:

Be it known that I, ALBERT A. HIRSH, a citizen of the United States, residing at New York, in the county of New York and State of New York, have invented certain new and useful Improvements in Tooth Cleaners, of which the following is a specification, reference being had therein to the accompanying drawing.

10 This invention relates to certain new and useful improvements in tooth cleaners, the object being to provide a tooth cleaner in the form of a thread or floss having a knob at each end to facilitate the manipulation 15 of the cleaner in cleaning the teeth so as to remove foreign matter from between the teeth for cleaning the teeth.

Another object of my invention is to provide a tooth cleaner which is so constructed 20 that it can be readily packed in a small box so that the cleaners can be carried in the pocket to be used as desired.

Another and further object of the invention is to provide novel means for securing 25 the knobs on the end of the thread so that they will be rigidly fastened thereto.

Other and further objects and advantages of the invention will be hereinafter set forth and the novel features thereof defined by 30 the appended claims.

In the drawings,

Figure 1 is a perspective view of my improved construction of tooth cleaner; and

Figure 2 is a vertical section through the knobs, showing the thread in elevation.

In carrying out my invention I employ a thread or floss 1 having knobs 2 arranged at each end. The knobs 2 are provided with bores 3 through which the thread is adapted 40 to pass. Formed adjacent each end of the thread is a knot 4.

Extending transversely through the knob

at right angles to the bores 3 are bores 5 which intersect the bores 3 and into which are adapted to be driven plugs 6 so as to 45 securely fasten the ends of the threads in the knobs as clearly shown in Figure 2.

In securing the ends of the threads in the knobs, I preferably employ a cement so as to fasten the threads and the plugs 6 in 50 position.

While I have shown a tooth cleaner formed of a thread having knobs secured on its ends, in a particular manner, I am aware that these knobs can be secured in 55 various ways without departing from the spirit of my invention.

From the foregoing description it will be seen that I have provided a tooth cleaner comprising a thread or floss carrying a knob 60 at each end which can be gripped by the fingers so that the thread can be placed between the teeth and manipulated, thereby overcoming the difficulties now existing with a plain thread as now in use. 65

What I claim is:—

1. A tooth cleaner comprising a strand of thread, a knob having a bore to receive the ends of the thread, said knobs being provided with intersecting bores and plugs extending through said intersecting bores for securing the thread in position within said knobs. 70

2. A tooth cleaner comprising a pair of knobs having bores extending therethrough, 75 a thread having its ends extended through said bores, knots formed on the ends of said thread, said knobs being provided with intersecting bores and plugs extending through said intersecting bores for securing the ends 80 of said thread within said knobs.

In testimony whereof I hereunto affix my signature.

ALBERT A. HIRSH.
